UNITED STATES PATENT OFFICE

CHESTER E. RAHR, OF BROOKLINE, MASSACHUSETTS, ASSIGNOR, BY MESNE ASSIGNMENTS, TO THE PATENT AND LICENSING CORPORATION, OF BOSTON, MASSACHUSETTS, A CORPORATION OF MASSACHUSETTS

ROOFING

Application filed August 1, 1924. Serial No. 729,494.

This invention relates to roofing of the type composed of overlapping strips and is directed more particularly to a construction of a strip by which a marginal portion is so formed as to present a guide for the laying of the overlapping strip while the surface underlying the latter strip is so formed as to properly take cement for attaching the two strips together so that a weatherproof joint may be effected.

For a more complete understanding of this invention, reference may be had to the accompanying drawings in which

Figure 1 is a fragmentary plan of a piece of roofing showing one manner of forming the joint portion.

Figure 2 is a fragmentary plan showing the manner of overlapping adjacent sheets.

Figure 3 is a cross section on line 3—3 of Figure 2.

For purposes of illustration this invention is shown as applied to slate surfaced roofing in which the sheet material, commonly formed of fibrous material such as rag felt 25 impregnated and coated with asphalt has a weather-proofing surfacing of crushed slate applied thereto. According to this invention asphalt is applied to the otherwise completed roofing sheet 1 along a strip of uniform width

as at 2. This may be positioned centrally of the width of the sheet as indicated in Figure 1 which may then be cut along the line centrally of the strip 2 as shown by the dotted line 3, or the strip may be applied along one edge of the sheet only, in either case the finished product presenting a sheet having a strip along one edge coated with asphalt. If the sheet is to be cut, the coating strip is approximately double the width of that employed where the coating is applied along the edge of the sheet. This coating fills the interstices between the grains of surfacing, as shown more clearly in Figure 3, so that a plane surface is presented over which the edge of the overlying sheet may project and which may be properly surfaced to receive cement by which a weather tight joint between the adjacent sheets may be effected. This surfacing may be of sand or other comparatively fine granular material, or if desired it may be

of talc or mica, this coating serving not only to receive the cement, but also to prevent sticking of the strip portion when the roofing sheet is rolled, as for ease in handling. This coated strip not only furnishes a proper surface for the reception of cement, but also is of different appearance from the main portion of the sheet so as to furnish a guide by which the proper amount of overlap of the succeeding sheet of the roof may be readily determined, the edge of the overlying sheet being laid to the inner edge of the strip.

While as shown this strip of additional coating is applied to rough surfaced roofing, it might, if desired, be applied to smooth surfaced roofing, where it would also function not only as a guide to aid in laying the overlapping sheet but also could be surfaced in a manner to permit a better bond of the cement to be produced than could be had with the smooth surface of the exposed portion of the sheet.

Having thus described certain embodiments of this invention, it should be evident to those skilled in the art that other changes and modifications might be made therein without departing from its spirit or scope as defined by the appended claims.

I claim:

1. Roofing comprising surfaced sheet material having an additionally coated portion of one face presenting a surface more suitable than the remainder of said face to receive cement by which overlapping sheet material may be fixed thereto.

2. Roofing comprising sheet material having a surface suitable for exposure to weather, a portion of such surface being additionally coated to present a surface more suitable to receive cement by which overlapping sheet material may be fixed thereto.

3. Roofing comprising sheet material having a surface suitable for exposure to the weather, a portion of said surface in the form of a marginal strip of uniform width being additionally coated to present a surface more suitable to receive cement by which overlapping sheet material may be fixed thereto.

4. Roofing comprising fibrous sheet material impregnated and coated with asphalt and

- having a weatherproofing surfacing applied to one face thereof, a portion of said face being further coated with asphalt and a surfacing more suitable than the first surfacing for the application of cement by which overlapping sheet material may be fixed thereto.
5. Roofing comprising fibrous sheet material impregnated and coated with asphalt and having a weatherproof surfacing applied to one face thereof, said sheet having a further coating of asphalt applied thereto in a marginal strip of uniform width, and a surface coating of material more suitable than the first surfacing to receive cement applied 10 to said strip coating.
15. Roofing comprising fibrous sheet material impregnated and coated with asphalt and having a weather-proof surfacing of crushed slate applied to one face, said face having a further coating of asphalt applied to one portion 20 thereof, and a surfacing of fine granular material applied to said portion.
25. Roofing comprising fibrous sheet material impregnated and coated with asphalt and having a weather-proof surfacing of coarse grit applied to one face, said face having a further coating of asphalt applied to one portion thereof, and a surfacing of fine sand applied to said portion.
30. Roofing comprising sheet material having a rough weather-resistant surface, and having applied to a portion only material filling the interstices in the surface and presenting a comparatively smooth surface.
35. Roofing comprising sheet material having a rough weather-resistant surface, and having applied along one margin thereof material filling the interstices in the surface and presenting a comparatively smooth surface flush with the outer points of the 40 remainder of the sheet.

In testimony whereof I have affixed my signature.

CHESTER E. RAHR.
